UNITED STATES PATENT OFFICE.

ZIMMOND J. OLAF, OF MALVERN, PENNSYLVANIA.

CARBON-REMOVER.

1,368,965.

Specification of Letters Patent. Patented Feb. 15, 1921.

No Drawing.

Application filed August 17, 1917. Serial No. 186,702.

To all whom it may concern:

Be it known that I, ZIMMOND J. OLAF, a citizen of the United States, and a resident of Malvern, Chester county, Pennsylvania, 5 have invented certain Improvements in Carbon-Removers, of which the following is a specification.

My invention relates to compounds or compositions of matter employed to remove 10 carbon from the cylinders of internal combustion engines. While my improved carbon remover is particularly adapted for use for loosening carbon from the cylinders, pistons, valves, spark plugs and other parts 15 of an internal combustion engine, it may be employed under any conditions where deposits of carbon interfere with the proper operation of any mechanical device or moving part clogged by such deposit.

20 The important object of my invention is to provide a simple and efficient mixture, compound, or composition of matter, that will serve to loosen the carbon and render it friable, and permit it to be blown out 25 with the exhaust after it has been permitted to remain in contact with the carbon deposit for a period of a few hours.

The material forming the subject of my 30 invention may be introduced into the cylinders at any time after the motor has been stopped, and in practice I usually place a small portion of the compound or composition of matter in the cylinders at night, and after remaining in the same over night, 35 for instance, the loose carbon separated by the action of my improved compound may be blown out with the exhaust when the engine is started next day.

In carrying my invention into effect, I propose to mix together carbolic acid, alcohol and ammonia, which ingredients are well shaken together to insure thorough commingling, and they may be employed in approximately or substantially the following proportions:

45

Carbolic acid-----2 parts,
Alcohol-----3 parts,
Ammonia water 26°-----2 parts.

The several ingredients may be of the 50 usual commercial character, purchasable in the open market, and for the alcohol I may use wood alcohol. Aqua ammonia of 26° is preferably employed as giving satisfactory results, although ammonia water of different strengths may be successfully employed.

55

In use, I place about one ounce of my improved carbon remover in each cylinder, and the same may be introduced through 60 the spark plug opening; the latter being removed for the purpose and then replaced. If desired, the spark plug may be dipped in the mixture so that any carbon attached thereto may be loosened and subsequently 65 removed.

I claim:

A compound or composition of matter for removing carbon from gas engine cylinders and the like, comprising a mixture of carbolic acid, substantially two parts; a low boiling alcohol, substantially three parts; 70 and ammonia, substantially two parts.

ZIMMOND J. OLAF.
